UNITED STATES PATENT OFFICE.

FRANK S. ADAMS, OF BOSTON, MASSACHUSETTS, ASSIGNOR TO BROWN,
DURRELL & CO., OF SAME PLACE.

DESIGN FOR A SPOOL-RACK.

SPECIFICATION forming part of Design No. 23,869, dated December 11, 1894.

Application filed November 9, 1894. Serial No. 528,352. Term of patent 7 years.

To all whom it may concern:

Be it known that I, FRANK S. ADAMS, of Boston, in the county of Suffolk and State of Massachusetts, have invented and produced a new and original Design for Spool-Racks, of which the following is a specification, reference being had to the accompanying drawing, forming a part thereof.

The drawing represents a perspective view 10 of a rack embodying the said design.

The leading feature of my design consists in a circular base, a circular top, parallel vertical standards connecting the base and top, and parallel horizontal bars extending 15 across the spaces between the standards.

a represents the circular base, and *b* the circular top.

c c c represent the vertical standards extending from the base to the top, and *d d* represent the horizontal rods which extend across 20 the spaces between the standards.

I claim—

The design for spool racks substantially as shown and described.

In testimony whereof I have signed my 25 name to this specification, in the presence of two subscribing witnesses, this 5th day of November, A. D. 1894.

FRANK S. ADAMS.
